(71) Applicant: **i-Abra Limited**, Dunstable (GB)

* cited by examiner

(72) Inventors: **Greg Compton**, Dunstable (GB); **Peter Sanderson**, Dunstable (GB)

Primary Examiner — Omeed Agilee

(73) Assignee: **i-Abra Limited**, Toddington (GB)

(74) *Attorney, Agent, or Firm* — Mary L. Fox; Fortem IP LLP

(**) Term: **15 Years**

(21) Appl. No.: **29/772,748**

(57) **CLAIM**

(22) Filed: **Mar. 3, 2021**

The ornamental design for a biosample testing cartridge, as shown and described herein.

(51) **LOC (14) Cl.** **24-02**

DESCRIPTION

(52) **U.S. Cl.**

USPC **D24/224**

(58) **Field of Classification Search**

USPC D24/216, 222-228, 231, 232; D9/503, D9/504, 505, 520, 529, 549; D3/203.1-203.8; D7/509; D10/81
CPC B01L 3/50825; B01L 9/06; B01L 9/65; B01L 9/00; A61J 1/00; A61J 1/12; A61J 1/065; A61J 1/067

FIG. 1 is a front perspective view of a biosample testing cartridge.

FIG. 2 is a rear perspective view of the biosample testing cartridge shown in FIG. 1.

FIG. 3 is a front view of the biosample testing cartridge shown in FIG. 1.

FIG. 4 is a rear view of the biosample testing cartridge shown in FIG. 1.

FIG. 5 is a left side view of the biosample testing cartridge shown in FIG. 1.

FIG. 6 is a right side view of the biosample testing cartridge shown in FIG. 1.

FIG. 7 is a bottom view of the biosample testing cartridge shown in FIG. 1; and,

FIG. 8 is a top view of the biosample testing cartridge shown in FIG. 1.

The dot-dash broken lines depict the boundaries of the claimed design and form no part thereof.
